Alfred Tschinkel

UNITED STATES PATENT OFFICE.

HANS ADELMANN, OF NEW YORK, N. Y., ASSIGNOR TO HAM BOILER CORP., OF NEW YORK, N. Y., A CORPORATION OF NEW YORK.

DESIGN FOR A HAM-MOLD.

49,915.

Specification for Design.

Patented Nov. 21, 1916.

Application filed March 2, 1916. Serial No. 81,759. Term of patent 14 years.

To all whom it may concern:

Be it known that I, HANS ADELMANN, a subject of the Emperor of Germany, residing at New York, in the county of New York and State of New York, have invented a new, original, and ornamental Design for a Ham-Mold, of which the following is a specification, reference being had to the accompanying drawing, forming part thereof.

The figure is a perspective view of a ham mold showing my new design.

I claim:

The ornamental design for a ham mold, as shown.

HANS ADELMANN.

Witnesses:

PAUL SCHÜPPEL,
WILLIAM BOHNERT.
